Primary Examiner — Ieisha N Price

(74) Attorney, Agent, or Firm — Daniel M. Cohn;
 Howard M. Cohn**CLAIM**

The ornamental design for an sunroof mount as shown and described.

DESCRIPTION

FIG. 1 is a perspective view of an sunroof mount showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dash-dash broken lines in the drawings depict portions of the sunroof mount that form no part of the claimed design.
